10 Claims. (Cl. 173—12)

ABSTRACT OF THE DISCLOSURE

A motor driven torque wrench having a torque arm laterally extending from the motor housing. The torque arm is mounted so as to be capable of movement at some predetermined torque level which movement actuates a motor control switch. The switch opens an electrical circuit which breaks the power supply to the motor thereby causing the torque wrench to shut off.

Background of the invention

The present invention relates to a torque transmitting device for tightening a fastening member, such as a nut, bolt or screw to a predetermined torque. This device is of simple construction since it employs a minimum of components and, yet, can be easily adjusted to provide a wide range of torque values. Moreover, its construction provides for a constant and low frictional resistance of its moving components thereby providing for extremely accurate and constant torque values over a long period of time.

Although torque wrenches find wide application in industry, heretofore known wrenches have suffered from certain disadvantages which limit their utility. For example, most torque limiting wrenches include a load-engaging member and mechanism which will undergo pivotal or sliding movement so as to release the load-engaging member when a certain torque level is reached. The moving members of the release mechanism, however, are generally supported by complicated or delicate bearing means, pivot axes, etc. which are readily susceptible to wear from even minimal normal use of the wrench, thereby giving rise to varying frictional resistances which result in inaccurate torque values. To minimize such variable resistance problems, wrenches have been developed wherein the load-engaging member is linked to a lever arm which in turn is held in a normally fixed position by means of a magnet. In these wrenches, when some predetermined torque is exceeded, the lever arm is pulled away from the magnet thereby allowing the load-engaging member to slip or release. Such systems have not achieved wide spread commercial acceptance, however, due to several problems associated therewith. Thus, such wrench systems generally have a narrow torque value range since the magnet holds the lever arm with a constant force. Since a fixed range of torque values is undesirable, it has been proposed to provide moveable fulcrums whereby the force required to separate the lever arm from the magnet can be varied. However, this adds to the complexity and cost of the wrench and introduces operational problems in that the adjustment of the fulcrum so as to achieve different torque values generally requires at least partial disassembly of the wrench. Moreover, calibration of the wrench is difficult since movement of the lever arm relative to the magnet occurs in a direction transverse to the length of the housing, and therefore, extremely slight adjustments in the position of the fulcrum result in substantial variation in the force required to unseat the lever arm from the magnet.

2

Summary of the invention

From the foregoing, it will be recognized that a torque wrench is needed which is capable of providing a relatively large range of torque values and, yet, is simple in construction, inexpensive to manufacture and which affords extremely accurate results each time that it is used.

Accordingly, it is an object of this invention to provide a novel and improved device for applying a measured amount of torque to another structure.

A further object is to provide a torque wrench which is constructed and arranged to provide a range of torque values and which is capable of simple and accurate calibration.

Yet another object is to provide a torque-limiting wrench incorporating a simple, rugged mechanism having a low and constant frictional resistance for releasing the load-engaging member of the wrench upon reaching a predetermined torque value.

Other objects and advantages of the present invention will become apparent from a further reading of the description and the appended claims.

Briefly, the apparatus of this invention comprises a driven load-engaging member which is supported by a housing that is adapted for pivotal movement in response to the load engaging member reaching a predetermined torque value. An arm member extends outwardly from the housing and is in engageable relationship with control means for shutting off the driven load-engaging member. The arm member is restrained from actuating the control means, so as to shut off the load-engaging member, by resilient means, and the amount of torque required to effect such shut off can be easily and quickly varied by simple adjustment of the resilient means. The torque wrench of this invention is constructed such that there is a need for only one pivot connection as between the various components thereof. Accordingly, frictional resistance and wear factors which have plagued heretofore known torque wrenches are reduced to a minimum in the apparatus of this invention thereby providing a torque wrench of exceptional accuracy and long life.

Description of the drawings

In the accompanying drawings, in which one of various possible embodiments is illustrated,

FIGURE 1 is a top view of a torque wrench constructed in accordance with the invention with portions of the outer skin broken away to reveal details of internal structure;

FIGURE 2 is a rear-elevational view looking in the direction of line 2—2 of FIGURE 1 with portions of the outer skin broken away to show details of internal structure;

FIGURE 3 is a side sectional view taken along the line 3—3 of FIGURE 1;

FIGURE 4 is a side sectional view taken along line 4—4 of FIGURE 1; and

FIGURE 5 is a schematic electrical circuit diagram for one embodiment of the invention.

Like parts are indicated by corresponding reference characters throughout the several views of the drawing.

Description of the preferred embodiment

The torque wrench of this invention is shown in FIGURES 1—4 and comprises, as seen with particular reference to FIGURE 1, a casing or frame, indicated generally by reference numeral 10, which forms a hollow body, having top, bottom and side walls closed by a removable cover

plate 12 held in position by fastening means such as screws 14. Handle members 16 are threadedly secured to the side wall portion of frame 10. A motor 18 is partially disposed within the hollow frame 10 and is supported therein as hereafter discussed. Motor 18 is illustrated as being air driven although it will be appreciated that other types of motors could be employed, such as electric motors. A rotatable shaft or spindle 20 extends from and is driven by the motor and is provided with an end portion 22 which serves to retain frictionally on the load-engaging shaft 20 any suitable tool which it is desired to mount thereon, such as a socket wrench or screw driver for engaging a screw, bolt, nut or other member which is desired to be tightened to a predetermined degree of torque.

In the illustrated embodiment, motor 18, as is seen with reference to FIGURE 1, is driven by compressed air which is supplied to the wrench via line 24 and which is interconnected with wrench air line 26 by means of connector 28. Air flow for operating the torque wrench is controlled by solenoid valve 30 which is interconnected with motor 18 by air line 32. Solenoid valve 30 is opened and closed in response to control means capable of being actuated by the user of the torque wrench, such as switch 34 which is provided with push button 36 located in handle 16.

As best seen in FIGURE 2, motor 18 is supported by a housing 38 which is generally in the form of a collar or C-clamp member which substantially surrounds a portion of the peripheral surface of motor 18. Fasteners 40 serve to securely interconnect the motor 18 and housing 38 for unitary movement. Housing 38 is pivotally mounted for pivotal movement with respect to frame 10 by means of a fulcrum member 42 which is provided at each of its opposite end portions (FIGURE 3) with knife-edge 44 and 46. Fulcrum member 42 is secured to frame 10 by suitable fastening means as screws 48. A member 50 is secured to housing 38 by fasteners 52 and cooperates with fulcrum 42 by means of recessed or notch portions 54 and 56 at each of its ends which engage and cradle knife edges 44, 46, respectively. As best seen with reference to FIGURES 1 and 3, the motor and housing 38 are prevented from substantial longitudinal sliding motion along knife edges 44, 46 by means of pins 58 which extend through member 50 so as to be engageable with the knife edge portions of fulcrum member 42.

To release the load-engaging shaft 20 upon its reaching a certain torque level, additional control means spaced from housing 38 are provided. Thus, as best seen in FIGURE 4, a switch 60 having push button 62 is secured to frame 10 by fasteners 64 and is interconnected, along with switch 34, in a circuit, hereinafter described, for controlling the operation of solenoid valve 30.

Switch 60 is actuated in response to movement of an arm member 66 which extends outwardly from housing 38. Thus, one end portion 66a of arm member 66 is disposed within a slot formed in housing 38 and is secured thereto by fasteners 68. Secured by pins 70 to the opposite end of arm member 66 is a clevis member 72 having a threaded bore portion 74 extending therethrough. A finger 76 extends radially outwardly from clevis member 72 so as to be engageable with push button 62 of switch 60.

To position and control movement of the arm member 66, resilient means are provided which resist pivotal movement of the arm member. Thus, a stop member 78 is threadedly engaged with bore 74 and has a surface 80 which normally engages frame 10 due to the biasing action of a spring 82. As seen with reference to FIGURE 4, one end of spring 82 is disposed within a recess 84 provided in stop member 78 so as to minimize space requirements and the opposite spring end is supported by a threaded post 86 which is threadedly carried by frame 10 and in axial alignment with stop member 78. An adjustment nut 88 threadedly engages post 86 so as to enable easy and quick regulation of spring pressure, thereby providing for adjustment of the torque release value of the wrench. In order to permit calibration of the torque wrench to desired

torque release values, stop member 78 is provided with a bore 90 which is axially aligned with an opening 92 in frame 10. As seen with reference to FIGURE 4, calibration is accomplished by inserting the stem 94 of a known weight 96 through opening 92 and into bore 90 so as to load the arm member 66. Spring 82 is then adjusted through manipulation of post 86 to provide the desired torque release setting.

In operation, spring 82 biases stop member 78 into engagement with frame 10 and maintains knife edges 44, 46 in firm engagement with notch portions 54, 56. Finger 76, as seen in FIGURE 4, is accordingly, held in contact with push button 62 so as to close switch 60. The load engaging shaft 20 is engaged with a member to be tightened and the operator actuates switch 34 by means of push button 36 located in handle 16. At this point, as seen with reference to FIGURE 5, current flows through a time relay switch 102, switch 60 and circuit relay control 104. The circuit relay control 104 then closes circuit relays 100, 110 and 112 and opens circuit relay 106. Accordingly, the circuit through solenoid valve 30 is completed and the solenoid valve opens to permit air to energize motor 18 and drive shaft 20. At this same time, a time relay 108 is actuated due to the opening of circuit relay 106 and causes switch 102 to open after a period, of for example, about one second, so as to disconnect switch 34 from the circuit even in the event push button 36 is held depressed.

As the load engaging shaft 20 rotates in a clockwise direction as view in FIGURE 2, the motor 18 and housing 38, which is securely connected to the motor, are urged in a counterclockwise direction against the pressure of spring 82. When the desired predetermined degree of torque is reached, the force of spring 82 is overcome and housing 38 pivots about the knife edges 44, 46 and lever arm 66 rotates downward, as viewed in FIGURE 2, thereby opening switch 60. Accordingly, the circuit through circuit relay control 104 is opened thereby closing circuit relay 106 and opening circuit relays 100, 110 and 112 which de-energizes solenoid 30, shutting off motor 18. Spring 82 then causes housing 38 to pivot about fulcrum member 42 which carries stop member 78 into engagement with frame 10 and finger 76 into actuating engagement with switch 60 thereby allowing the cycle to be repeated. It will be noted upon examination of the circuit shown in FIGURE 5, that it is necessary for the operator to release the push button 36 of switch 34 and then depress it in order to actuate the motor after the desired torque value has been reached and arm member 66 actuated switch 60. This is desirable to prevent actuation of the torque wrench upon its being removed from the load in the event the operator has maintained push button 36 in a depressed position. As an additional safety factor, a wrench shut off switch, such as switch 114 (FIGURE 1) can be provided to completely de-energize the entire circuit arrangement as shown in FIGURE 5 thereby preventing accidental actuating of the torque wrench.

The torque wrench described hereinabove has been used with great success and found to provide extremely accurate and uniform torque values. Moreover, it is readily adaptable to provide a wide range of torque values, such range only being limited by the size and quality of construction of its components. The size and weight of the wrench are naturally determined primarily by the conditions under which it will be used; however, due to its generally symmetrical shape the wrench can be constructed to provide any range of torque values without fear of weight problems since the wrench can readily be supported by cable 116 (FIGURE 1) which is part of a counter balance arrangement (not shown).

From the foregoing description, it is seen that the torque wrench of this invention does not employ, as found in heretofore known wrenches, a complicated mechanism for releasing the load engaging member at a predetermined torque. The torque wrench employs only a single pivotal connection as between the various components thereof

and due to the knife edge construction of this pivot connection it is not subject to any appreciable wear and provides for a minimum of frictional resistance. Likewise, unlike other torque wrenches there are no catches or other fittings subject to wear, thereby greatly increasing the working life and accuracy of the torque device of this invention.

Accordingly, the above-mentioned objects of this invention have been fulfilled and it will be understood that modifications and variations may be effected without departing from the scope of the novel concepts of the present invention as defined in the appended claims.

I claim:

1. A torque wrench comprising a frame member, a housing, a rotatable shaft supported by the housing and having a portion adapted to be operatively connected in torque transmitting relation to a member to be tightened, driving means for rotating said shaft, control means effective at times to actuate said driving means, additional control means spaced from said housing and being effective at times to deactivate said driving means, an arm member extending from said housing and having a portion in engageable relationship with said additional control means, and pivot means for allowing pivotal movement of said housing with respect to said frame, said pivotal movement of said housing being operative to effect simultaneous pivotal movement of said arm member, and said additional control means being adapted to be activated in response to the movement of said arm member.

2. A torque wrench according to claim 1 wherein said pivot means comprises a fulcrum having at least one knife edge, and wherein said housing pivots about said knife edge.

3. A torque wrench according to claim 1 wherein said control means comprises an electrical circuit and a first switch means operative to open and close said circuit, and wherein said additional control means comprises a second switch means operative to open and close said circuit.

4. A torque wrench according to claim 1 including resilient means which resists pivotal movement of said arm member in a direction opposite to the direction of rotation of said shaft when said shaft is driven by said driving means.

5. A torque wrench according to claim 1 having a stop member disposed so as to limit pivotal movement of said housing and arm member in the direction of rotation of said shaft when said shaft is driven by said driving means, and further having adjustable resilient means normally biasing at least one of said housing and arm members in said direction.

6. A torque wrench according to claim 5 wherein said stop member is carried by said arm member so as to be in engageable relationship with said frame, and wherein said adjustable resilient means comprises a spring which normally holds said stop member in contact with said frame.

7. A torque wrench according to claim 1 wherein said driving means constitutes a motor and said control means comprises an electrical circuit to actuate the motor and a first switch operative to open and close said circuit, 5 wherein said additional control means comprises a second switch which is spaced from said housing and operative to open and close said circuit in response to movement of said arm member, wherein said pivot means comprises a fulcrum having at least one knife edge, said fulcrum being carried by one of said housing and frame members, wherein one of said frame and arm members carries a stop member to limit pivotal movement of said arm member in the direction of rotation of the shaft when said shaft is driven by said motor, and wherein said wrench includes adjustable resilient means, said arm member being carried by said housing and being normally biased in said direction of shaft rotation by said adjustable resilient means.

8. A torque wrench according to claim 1 wherein the 20 driving means comprises a motor, said motor being supported by said housing, wherein the pivot means comprises a fulcrum having a knife edge which is carried by said frame member, wherein said control means comprises an electrical circuit and a first switch operative to 25 open and close said circuit, said wrench further including a stop member disposed so as to limit pivotal movement of said housing in the direction of rotation of the shaft when said shaft is rotated by said rotor, and adjustable resilient means acting on the arm member so as to resist 30 pivotal movement of said arm in a direction opposite to the direction of rotation of said shaft when said shaft is driven by said motor, said arm member being carried by said housing and extending outwardly therefrom in a direction generally normal to the axis of rotation of said 35 shaft.

9. A torque wrench according to claim 8 wherein the housing is provided with notch means disposed so as to cooperate with said knife edge portion of said fulcrum, said fulcrum and housing being positioned such that said knife edge portion is cradled in said notch means.

10. A torque wrench according to claim 9 wherein 40 said stop member is spaced from said housing and carried by said arm member so as to be engageable with said frame, and wherein said adjustable resilient means is 45 spaced from said housing and normally holds said stop member in contact with said frame.
